MANUFACTURE OF FORMALDEHYDE

Art C. McKinnis, Long Beach, Calif., assignor to
 Union Oil Company of California, Los Angeles,
 Calif., a corporation of California

Application April 3, 1950, Serial No. 153,630

9 Claims. (Cl. 260—604)

1

This invention relates to the manufacture of formaldehyde, and in particular concerns an improved process for the production of formaldehyde by the partial oxidation of methane or natural gas.

It is known that formaldehyde may be formed by the partial oxidation of methane or natural gas, and a number of processes have been proposed for adapting the reaction to the production of formaldehyde on a commercial scale. All of such processes involve the use of oxygen or air as the oxidizing agent, and most of them employ metal oxides or nitrogen oxides as catalysts to promote the reaction. However, none of such proposed processes has met with commercial success, primarily because of the poor yield of formaldehyde realized and because of technical difficulties inherent in the manner in which the process is effected. Insofar as I am aware, none of such processes has been able to produce formaldehyde in yields greater than 25 per cent of theoretical, based on the methane consumed. Furthermore, in those processes in which nitrogen oxides are employed as catalysts, corrosion and purification problems arise as a result of the nitrogen oxides occurring in the product in the form of nitric and/or nitrous acids. Attempts have also been made to oxidize methane to formaldehyde employing nitrogen dioxide as the sole oxidizing agent, but here again the yields of formaldehyde obtained were only about 20 per cent of theoretical, based on the methane consumed.

It is accordingly an object of the present invention to provide an improved process for the production of formaldehyde from methane or natural gas.

Another object is to provide a process whereby methane or natural gas is partially oxidized to formaldehyde by means of an oxidizing agent which can readily be regenerated for re-use in the process.

A further object is to provide a process whereby methane or natural gas is oxidized to form formaldehyde in yields higher than those heretofore realized.

Other objects will be apparent from the following detailed description of the invention, and various advantages not specifically referred to herein will occur to those skilled in the art upon employment of the invention in practice.

I have found that the above objects and attendant advantages may be realized in a process whereby methane or natural gas is partially oxidized to formaldehyde by reaction with nitrogen dioxide at somewhat elevated temperatures over

2

a relatively short period of time. More particularly, I have found that under certain conditions certain mixtures of nitrogen dioxide and methane or natural gas undergo combustion in the absence of oxygen to form formaldehyde in good yield, and that substantially all of the formaldehyde so formed may be recovered by quickly removing the combustion products from the combustion zone and cooling them to a temperature below the decomposition temperature of the formaldehyde product. In previous attempts to oxidize methane with nitrogen dioxide, the reactant gas mixture was subjected to temperatures of about 440°—630° C. for periods of time ranging from about 3 to about 18 seconds, and the yield of formaldehyde obtained was at best only about 20 per cent of theoretical, based on the methane consumed. Presumably, such low yields were at least in part due to the fact that the formaldehyde initially formed became decomposed or underwent further reaction during the relatively long period of time it was subjected to the elevated temperature. I have now found that yields as high as 40 per cent of theoretical, based on the methane consumed, may be obtained by subjecting the reactant gas mixture to similar reaction temperatures for much shorter periods of time, e. g., 0.001—0.5 second. The invention thus consists in the process for the production of formaldehyde whereby a substantially oxygen-free gaseous reactant mixture of nitrogen dioxide and methane or natural gas is subjected to an elevated temperature sufficient to initiate combustion of the mixture, and the products of the combustion are removed from the combustion zone and are cooled to a temperature below the decomposition temperature of formaldehyde within about 0.5 second of their formation. According to a preferred embodiment of the invention, such process is effected simply by burning a mixture of nitrogen dioxide and methane or natural gas in the substantial absence of oxygen while controlling the size and shape of the flame so that the time of passage of the reactant gas therethrough is less than about 0.5 second.

The reaction whereby formaldehyde is formed according to the process of the invention may be represented by the equation:

55 (As is well known, nitrogen dioxide exists in equilibrium with its dimer, nitrogen tetroxide, and accordingly it will be understood that where the term nitrogen dioxide is employed herein such term refers to the equilibrium mixture of

nitrogen dioxide and nitrogen tetroxide that exists under the prevailing conditions of temperature and pressure.) Since the reaction is effected in the absence of oxygen, there is no tendency for the nitric oxide by-product to react with oxygen and the water formed in the reaction to form corrosive nitric and/or nitrous acids. Furthermore, such nitric oxide by-product can easily be isolated from the formaldehyde and water and is very readily oxidized back to nitrogen dioxide merely by contacting with air, so that the process may be operated in a continuous cyclic manner with continuous regeneration of the nitrogen dioxide reactant. Such mode of operation is illustrated diagrammatically by Figure 1 of the accompanying drawing, and essentially comprises (1) a production step wherein a proportioned mixture of nitrogen dioxide and methane or natural gas is caused to undergo combustion whereby formaldehyde, nitric oxide and water are formed according to the above reaction equation, (2) a separation step whereby the nitric oxide by-product and unreacted methane are separated from the formaldehyde and water and (3) a regeneration step wherein the gaseous mixture of nitric oxide and unreacted methane is mixed with oxygen or air whereby the nitric oxide is spontaneously oxidized to nitrogen dioxide and there is thus obtained a recycle gas mixture comprising nitrogen dioxide and methane. Such mixture is mixed with sufficient methane to make up for that consumed in the production step and with sufficient nitrogen dioxide to make up for incidental losses, and the resulting mixture is introduced into the production step as feed gas.

From the reaction equation given above it would appear that two moles of nitrogen dioxide should be provided for each mole of methane or natural gas, and that the reactant gas mixture should accordingly comprise about 67 per cent by volume of nitrogen dioxide and about 33 per cent by volume of methane or natural gas. I have found, however, that when a gas mixture of such composition is employed substantially all of the methane is oxidized to carbon monoxide and carbon dioxide, and very little formaldehyde occurs in the product gas. Accordingly, I prefer to employ a feed gas mixture containing an excess of methane or natural gas, and particularly one in which the mole ratio of hydrocarbon to nitrogen dioxide is between about 1:1 and about 5:1. In feed gas mixtures consisting only of methane or natural gas and nitrogen dioxide, such mole ratios are attained in gas mixtures consisting of from about 50 to about 85 per cent by volume of methane or natural gas and from about 50 to about 15 per cent by volume of nitrogen dioxide. A feed gas mixture consisting of about 65 per cent by volume of methane or natural gas and about 35 per cent by volume of nitrogen dioxide has been found particularly satisfactory. As a result of the use of such feed gas mixtures containing excess methane, the product comprises a considerable quantity of unreacted methane but no problem of separation arises since the unreacted methane and nitric oxide may be physically separated from the aqueous formaldehyde as a gas mixture. If desired, such gas mixture may be further treated to separate the methane from the nitric oxide, but ordinarily the mixture is passed directly to the regeneration step where the nitric oxide is oxidized with air to nitrogen dioxide without interference from the methane.

The reaction may be effected simply by sub-

jecting the feed gas mixture to a reaction temperature between about 450° C. and about 700° C. for a period of time ranging from about 0.001 to about 0.5 second, as for example by passing the gas mixture through a heated tube of such length that the desired contact time is attained. Preferably, however, the gas mixture is preheated and is then passed to a burner where it is ignited and allowed to burn with a free self-sustaining flame. In order that the residence time of the combustion products within the flame be less than about 0.5 second, it is desirable that the flame take the form of a thin flat disc of only a few millimeters in thickness, i. e., it is desirable that the dimension of the flame in the direction of its propagation be small in comparison with its diameter. A flame of such shape is obtained when the velocity at which the reactant gas mixture is supplied to the flame, i. e., the flow velocity, exceeds the velocity of propagation of the flame, i. e., the flame velocity. Since the latter depends upon the temperature of the reactant gas mixture supplied to the flame, i. e., the preheat temperature, the shape of the flame, and hence the reaction time, may be controlled by controlling the preheat temperature and/or the flow velocity. Usually it is desirable to preheat the gas mixture to a temperature of about 100°-400° C. and to adjust the flow velocity accordingly to obtain the desired disc-shaped flame. Various types of burners may be employed, two of which are illustrated in Figures 2 and 3 of the accompanying drawing.

Referring now to Figure 2 of said drawing, the burner therein illustrated in cross-section consists of a tubular body portion 11 having constricted ends 12 and 13 forming a feed gas inlet and a product gas outlet, respectively. Positioned within body 11 are perforate retaining discs 14 and 15 which serve to retain a gas-permeable packing 16 comprising a refractory material such as unglazed porcelain chips, cracked silica, porcelain or glass beads, etc. Retaining disc 14 may be of the nature of a porous diaphragm constructed, for example, of unglazed porcelain, but in order to minimize the pressure drop through the burner it is more usually constructed in the form of a screen or a plate having discrete perforations. Retaining disc 15, which forms the burner face, may likewise be a screen or a perforate plate or the like, but is preferably of the nature of a porous diaphragm constructed of unglazed porcelain, sintered alumina, quartz or silica, porous carbon or graphite, etc. The packing 16 serves to conduct heat away from the burner face and to prevent the flame from flashing back into the feed gas inlet. By properly adjusting the rate of feed gas flow so that the flow velocity exceeds the flame velocity, the flame may be maintained in the form of a thin flat disc 17 through which the reaction gases pass and within which the reaction takes place. In operating this type of burner, the feed gas mixture, which has preferably been preheated, is passed into the burner through inlet 12 and is ignited on the downstream side of the burner face 15 by suitable ignition means not shown. The rate of gas flow is controlled so that the dimension of the flame in the direction of its propagation is small enough that the time of passage of the reaction gas through the flame is less than about 0.5 second, preferably about 0.001 to about 0.05 second. The combustion products are withdrawn from the burner through outlet 13 and are cooled and treated to separate the components thereof as is hereinafter more fully explained.

The burner illustrated in cross-section in Figure 3 of the drawing makes use of the heat contained in the combustion products to preheat the feed gas. This burner comprises a tubular body portion 21 having a closed end 22 and an open end 23 adapted to receive inlet conduit 24. Body portion 21 is also fitted with a side-arm 25 which serves as a product gas outlet. Inlet conduit 24 is substantially coaxial with body portion 21 and extends within the same to a point at least beyond side-arm 25. If desired, the assembly may be so constructed that the distance which inlet conduit extends within the body portion may be varied at will. In operating this type of burner, the feed gas mixture is passed into the inlet conduit 24 and is ignited at the open end thereof within the body portion 21 by heating closed end 22 of body portion 21 or by suitable igniting means, not shown. By suitably adjusting the rate of feed, the flame may be caused to take the form of a thin flat disc 26. The reaction gases pass through the flame, reverse their direction of flow and pass through the annular space between body portion 21 and inlet conduit 22, and finally are withdrawn through the side-arm 25. As the hot product gases pass through the annular space between the body portion and the inlet conduit they serve to preheat the feed gas passing through the inlet conduit by heat-exchange through the walls thereof. By adjusting the distance between the open end of the inlet conduit and the side-arm, the amount of such preheating may be readily controlled.

While the main reaction which occurs under the conditions herein specified is expressed by the reaction equation given above, various side reactions also occur with the formation of carbon monoxide and carbon dioxide. Accordingly, the product gas will consist essentially of a mixture of formaldehyde, water vapor, nitric oxide, carbon monoxide, carbon dioxide, and unreacted methane. Substantially all of the nitrogen dioxide is converted to nitric oxide, so that at most only traces of unreacted nitrogen dioxide occur in the product gas. Treatment of such product gas for the separation of the various components may be effected in various ways. For example, the gas may first be scrubbed with water whereby the formaldehyde and water vapor are selectively absorbed and thus separated from other components of the mixture. In order to prevent oxidation of the nitric oxide and the consequent formation of nitrous and/or nitric acid in the aqueous formaldehyde solution, the scrubbing operation is preferably carried out in the absence of oxygen, and the scrubbing water should accordingly be boiled or otherwise treated to remove dissolved oxygen. The aqueous solution of formaldehyde thus obtained may have a concentration as high as 15 per cent by weight, and may be marketed as such or concentrated to higher strength by known methods. After removal of the formaldehyde from the product gas by scrubbing with water, the residual gas may be treated with aqueous calcium hydroxide whereby the carbon dioxide is removed in the form of calcium carbonate. The residual mixture of methane, nitric oxide and carbon monoxide is then mixed with oxygen or air whereby the nitric oxide is oxidized to nitrogen dioxide for re-use in the process. Since the reactant gas mixture should be substantially free of oxygen, the quantity of oxygen or air added to the residual mixture of unreacted methane and nitric oxide should be sufficient only to oxidize the amount of nitric

oxide present to nitrogen dioxide, and is usually slightly less than this quantity.

The side reaction whereby carbon monoxide is formed is accompanied by a second side reaction whereby the carbon monoxide so formed is oxidized to carbon dioxide. The rates of these two reactions are approximately equal, and accordingly the formation of carbon monoxide may be suppressed by providing an equilibrium amount of carbon monoxide in the reactant gas mixture. When operating in a continuous manner with regeneration of the nitrogen dioxide and recycling of the same along with the unreacted methane to the feed gas, it is not necessary to treat the recycle gas for the removal of carbon monoxide. The latter is allowed to accumulate until the equilibrium concentration is attained, whereupon further formation of carbon monoxide is suppressed, in accordance with mass action principles. By suppressing formation of carbon monoxide in this manner, somewhat improved yields of formaldehyde are obtained. Other methods of treating the product gas for the desired separation of the various components may be employed, and may be based on selective adsorption on solid adsorbents, selective absorption in various solvents, and selective chemical reactions.

The following examples will illustrate several ways in which the principle of the invention may be applied, but are not to be construed as limiting the invention.

Example I

35 A reactant gas mixture consisting of about 80 per cent by volume of natural gas and about 20 per cent by volume of nitrogen dioxide is pre-heated to a temperature of about 400° C. and is supplied to a burner of the type illustrated in 40 Figure 2 of the accompanying drawing. The mixture is ignited at the burner face, and the feed rate is adjusted so that the flame takes the form of a thin flat disc of about 2 mm. thickness in the direction of its propagation and about 1 45 cm. in diameter. The residence time of the gas mixture within the flame is about 0.1 second. The products of the combustion are collected and countercurrently scrubbed with water from which the dissolved oxygen has been expelled by boiling. 50 Analyses of the aqueous solution and of the residual gas show that approximately 40 per cent of the methane consumed in the reaction is converted to formaldehyde.

Example II

55 The burner employed is of the reverse-flow type illustrated by Figure 3 of the accompanying drawing. The body of the burner has an inside diameter of about 5 cm., and the inlet conduit has a diameter of about 4 cm. and extends inside the body for a distance of about 10 cm. beyond the outlet conduit and to within about 2 cm. of the closed end of the body. Ignition of the reactant gas mixture at the end of the inlet conduit is secured by heating the closed end of the burner. The outlet conduit leads directly to a countercurrent scrubbing tower wherein the product gas is cooled and scrubbed with water from which dissolved oxygen has been expelled by boiling. 60 The residual gas from the water scrubber is then passed through an aqueous slurry of calcium hydroxide, whereby carbon dioxide is removed as insoluble calcium carbonate, and is thence mixed with sufficient oxygen to react with the nitric 70 oxide present to form nitrogen dioxide, and is

finally introduced into the feed gas stream. After the attainment of steady state conditions, the preheat temperature of the reactant gas before entering the flame is about 350° C., with the gas being supplied to the flame at a linear velocity of about 10 cm./sec. The flame takes the form of a thin flat disc which is about 3 mm. thick in the direction of its propagation. The residence time of the gas within the flame is thus about 0.03 second. The reactant gas supplied to the burner consists of about 0.31 mole of fresh feed gas, consisting of about 94.6 per cent by volume of methane and about 5.4 per cent by volume of nitrogen dioxide, and about 8.7 moles of recycle gas consisting of about 12.7 per cent by volume of regenerated nitrogen dioxide, 19.4 per cent by volume of unreacted methane, and 68.9 per cent by volume of carbon monoxide. The mole ratio of methane to nitrogen dioxide in the reactant gas is thus about 2:1. Analysis of the aqueous solution taken from the water scrubber shows it to contain about 0.088 mole of formaldehyde. The residual gas contains about 2.0 moles of unreacted methane, about 6.0 moles of carbon monoxide, and about 1.0 mole of nitric oxide. By adding 0.5 mole of oxygen to the residual gas, the nitric oxide is oxidized to nitrogen dioxide to form the recycle gas of the aforementioned composition.

In the foregoing Example II, the reactant gas mixture supplied to the flame consisted of about 2.0 moles of methane, about 1.017 moles of nitrogen dioxide, and about 6.0 moles of carbon monoxide. As previously stated, the methane to nitrogen dioxide ratio should be between about 1:1 and about 5:1. The equilibrium amount of carbon monoxide varies depending upon the specific conditions under which the reaction is effected, but usually amounts to about 3 moles per mole of methane. If desired, the advantage of providing the equilibrium amount of carbon monoxide in the reactant gas mixture may be realized in single-pass operation simply by adding such amount from an external source to the mixture of methane and nitrogen dioxide. Ordinarily, however, continuous operation with regeneration of the nitrogen dioxide and recycling of the unreacted methane and regenerated nitrogen dioxide is preferred, in which case the equilibrium amount of carbon monoxide is attained in the system simply by allowing it to accumulate until its rate of oxidation is equal to its rate of formation.

As will be apparent to those skilled in the art, many variations with respect to the reactor design, product recovery system, etc. are possible within the scope of the invention, and various engineering techniques may be applied to the practice of the invention on a large scale. Thus, for example, the system may be so designed that the reaction can be carried out under reduced pressure. The burners may take various forms and may be constructed of various refractory materials which are chemically inert to the reactant gas mixture under the conditions prevailing. If desired, a multiplicity of burners may be mounted in a single enclosed space so as to enable the production and collection of a large volume of product gas without necessitating a complicated manifold system. Similarly, various methods of treating the product gas for the separation of various components or groups of components thereof may be employed, and the formaldehyde product may be concentrated or otherwise treated by any of the various procedures known in the art.

Other modes of applying the principle of my invention may be employed instead of those explained, change being made in the materials or methods employed, provided the step or steps stated by any of the following claims, or the equivalent of any such stated step or steps, be employed.

I, therefore, particularly point out and distinctly claim as my invention:

1. The process for the production of formaldehyde which comprises forming a substantially oxygen-free combustible mixture of nitrogen dioxide and a hydrocarbon gas selected from the class consisting of methane and natural gas, said mixture containing from about one to about five moles of the hydrocarbon per mole of nitrogen dioxide, subjecting said mixture to a reaction temperature substantially equal to the flame combustion temperature of said mixture for from about 0.001 to about 0.5 second and in the substantial absence of oxygen, and thereafter separating formaldehyde from the products of the reaction.

2. The process of claim 1 wherein the hydrocarbon gas is methane.

3. The process of claim 1 wherein the hydrocarbon gas is natural gas.

4. The process for the production of formaldehyde which comprises forming a substantially oxygen-free combustible mixture of nitrogen dioxide and methane containing from about one to about five moles of methane per mole of nitrogen dioxide, supplying said mixture to a flame maintained by the combustion of said mixture in the substantial absence of oxygen at a velocity such that the residence time of said mixture within said flame is between about 0.001 and about 0.5 second, and thereafter separating formaldehyde from the products of the combustion.

5. A process for the production of formaldehyde which comprises forming a substantially oxygen-free combustible mixture of nitrogen dioxide and methane containing from about one to about five moles of methane per mole of nitrogen dioxide, preheating said mixture to a temperature between about 100° C. and about 400° C., supplying the preheated mixture to a flame maintained by the combustion of said mixture in the substantial absence of oxygen, the rate of supply being controlled so that the flame takes the shape of a thin flat disc having its dimension in the direction of its propagation small with respect to its diameter and so that the time of passage of said mixture through said flame is between about 0.001 and about 0.5 second, and thereafter separating formaldehyde from the products of the combustion.

6. The process of claim 5 wherein the mixture is preheated by indirect heat exchange against the products of the combustion.

7. The process for the production of formaldehyde which comprises forming a substantially oxygen-free combustible feed gas mixture of nitrogen dioxide and a hydrocarbon gas selected from the class consisting of natural gas and methane, said mixture containing from about one to about five moles of the hydrocarbon per mole of nitrogen dioxide, supplying said mixture to a flame maintained by the combustion of said mixture in the substantial absence of oxygen at a velocity such that the residence time of said mixture within said flame is between about 0.001 and about 0.5 second, separating formaldehyde and water from the products of the combustion, adding to the residual gas sufficient oxygen to oxidize

the nitric oxide contained therein to nitrogen dioxide, and employing said nitrogen dioxide in the formation of a further quantity of said feed gas mixture.

8. The process for the production of formaldehyde which comprises forming a substantially oxygen-free combustible feed gas mixture of nitrogen dioxide, methane and carbon monoxide, said mixture containing from about one to about five moles of methane per mole of nitrogen dioxide and an equilibrium amount of carbon monoxide, supplying said mixture to a flame maintained by the combustion of said mixture in the substantial absence of oxygen at a velocity such that the residence time of said mixture within said flame is between about 0.001 and about 0.5 second, and thereafter separating formaldehyde from the products of the combustion.

9. The process for the production of formaldehyde which comprises forming a substantially oxygen-free combustible feed gas mixture of methane, nitrogen dioxide and carbon monoxide, said mixture containing from about one to about five moles of methane per mole of nitrogen dioxide and an equilibrium amount of carbon monoxide, preheating said mixture by indirect heat-exchange against hot product gas, supplying the preheated mixture to a flame maintained by the combustion of said mixture in the substantial absence of oxygen at a velocity such that the

5 flame takes the form of a thin flat disc having its dimension in the direction of its propagation such that the time of passage of said mixture through said flame is between about 0.001 and about 0.5 second, separating formaldehyde, water vapor and carbon dioxide from the products of the combustion, adding to the residual gas comprising unreacted methane, nitric oxide and carbon monoxide an amount of oxygen only sufficient to oxidize said nitric oxide to nitrogen dioxide, and employing the resulting gas mixture for the formation of a further quantity of said feed gas mixture.
